UNITED STATES PATENT OFFICE.

EDWARD M. BARNES, OF HASTINGS, MICHIGAN, ASSIGNOR TO AMERICAN UTILITIES COMPANY, OF ST. JOSEPH, MICHIGAN.

ELECTRIC WATER-PURIFIER.

1,264,593.

Specification of Letters Patent. Patented Apr. 30, 1918.

Application filed June 30, 1917. Serial No. 177,955.

To all whom it may concern:

Be it known that I, EDWARD M. BARNES, a citizen of the United States, residing at Hastings, Michigan, have invented certain 5 new and useful Improvements in Electric Water-Purifiers, of which the following is a specification.

This invention relates to improvements in electric water purifiers.

10 The objects of the invention are:

First, to provide a device of this type which is simple in construction, cheap to manufacture, and easily assembled and disassembled.

15 Second, to provide a device of this kind comprising a separable electrical connection whereby the source of current may be disconnected from the electrode at the place of use.

20 Further objects, and objects relating to details and economies of construction and operation will definitely appear from the detailed description to follow.

I accomplish the objects of my invention by the devices and means described in 25 the following specification. The invention is clearly defined and pointed out in the claims.

20 A structure constituting a preferred embodiment of my invention is illustrated in the accompanying drawing forming a part of this specification, in which:

30 Figure I is a detail side elevation of my improved structure, partially in section along the line 1—1 of Fig. II.

35 Fig. II is a detail view mainly in longitudinal section on a line corresponding to line 2—2 of Fig. I.

Fig. III is a transverse section on the line 40 corresponding to line 3—3 of Fig. I.

Fig. IV is a transverse section on a line corresponding to line 4—4 of Fig. I.

Fig. V is a detail longitudinal section, 45 corresponding to the section shown in Fig. I, of a modified embodiment of my invention.

In the drawing, similar reference characters refer to similar parts throughout the several views, and the sectional views are 50 taken looking in the direction of the little arrows at the ends of the section lines.

Referring to the drawing, the reference characters 1 indicate complementary elongated body members having registering central longitudinal slots 3. The lower end

walls of the slots 3 are provided with spaced recesses 4 for receiving the lower ends of the electrodes 5. The upper end walls of the slots are each provided with a pair of spaced slots 6 which when the body members are assembled form a pair of spaced apertures for receiving the upper ends of the electrodes 5. Each of the slots 6 has a lateral off-set 7 for receiving the laterally extending upper ends 8 of the electrodes 5. 60 The contact pins 9 have screw-threaded engagement with the lugs 8 and extend through the upper ends of the body members. The body members are secured together by the bolts 10. A detachable cap 70 which forms a handle for manipulating the device is secured to the upper ends of the body members and comprises the complementary members 11 having a greater dimension in one direction than in the other 75 as shown in Figs. I and II. The cap members 11 have in their opposed faces the complementary grooves 12 which connect the complementary recesses 13 with the opposite ends of the cap. 80

85 Socket contacts 14, located in the recesses 13, are adapted to receive the upper ends of the pin contacts 9 and the lower ends of the conductors 15 which are secured in the upper ends of the grooves 12. A flexible cord protector 16 of well-known construction is secured in the upper end of the cap. Bolts 17 secure the two halves of the cap together.

90 In the modified embodiment of my invention illustrated in Fig. V the cap members are dispensed with and the upper ends of the body members are shown with enlarged opposed recesses 18 into which the upper ends of the electrodes 5' project, the said electrodes being prevented from working upwardly by the lateral projections 19 of the insulation block 20. Socket terminals 21 for receiving the ends of conductors are secured to the ends of the electrodes 5' by means of the screws 22. The upper ends of the body 95 members are recessed at 23 to receive the cord protector 16. Bolts 24 secure the two body members together.

100 The body members and cap may be constructed of any suitable insulating material but I prefer to construct them of molded hard rubber, porcelain, or glass. The electrodes are preferably made of aluminum, or an aluminum alloy.

105 Having thus described my invention, what

I claim as new and desire to secure by Letters Patent is:

1. In a structure of the class described, the combination with a body of insulating material having a slot therethrough, of electrodes having their faces spaced, contacts connected with said electrodes and extending through the top of said body, and a handle comprising a cap detachably secured to said body provided with a pair of contacts adapted to coöperate with said first named contacts.
2. In a structure of the class described, the combination with a body of insulating material having a slot extending therethrough, of electrodes secured to said slots in spaced relation, contact pins secured to said electrodes and extending through a wall of said body, a handle comprising a cap detachably secured to said body and provided with contacts coöperating with said first named contacts.
3. In a structure of the class described, the combination with a pair of complementary body members of insulating material having registering longitudinal slots, the bottom end walls of said slots being provided with a pair of spaced registering recesses for receiving the lower end of electrodes and the upper end walls of said longitudinal slots being provided with a pair of spaced registering slots having lateral offsets, the last named slots forming a pair of spaced apertures when the members are assembled, electrodes disposed in said apertures having lateral lugs received in the offset portions thereof, the lower ends of said electrodes being disposed in said recesses, and means for securing said body members together.
4. In a structure of the class described, the combination with a pair of complementary

body members of insulating material having registering longitudinal slots, the upper end walls of said slots being provided with a pair of spaced registering slots having lateral offsets, the last named slots forming a pair of spaced apertures when the members are assembled, electrodes disposed in said apertures having lateral lugs received in the offset portions thereof, and means for securing said body members together. 45

5. In a structure of the class described, the combination with a pair of complementary body members of insulating material having registering longitudinal slots, the upper end walls of said slots being provided with a pair of spaced registering slots, the last named slots forming apertures when the members are assembled, electrodes disposed in said apertures, means for securing said body members together, and contacts secured to said electrodes and extending through the upper ends of said body members. 50

6. In a structure of the class described, the combination of a pair of complementary body members of insulating material having registering slots therein, the upper end walls of said slots being provided with a pair of registering slots coacting when the members are assembled to form apertures, electrodes disposed in said apertures and extending into said first named slots, the opposed faces of said electrodes being spaced, and means for securing the said body members together. 55

In witness whereof, I have hereunto set my hand and seal in the presence of two witnesses. 60

EDWARD M. BARNES. [L.S.]
